UNITED STATES PATENT OFFICE.

GEORGE R. RICH, OF BATTLE CREEK, MICHIGAN.

VALVE GRINDER.

Application filed February 16, 1927. Serial No. 168,531.

This invention relates to valve grinders and more particularly to the clutch thereof which holds the poppet valve during the process of grinding its tapered seating face. 5 Tapered face poppet valves of internal combustion engines seat upon correspondingly tapered valve seats formed in the cylinder blocks of the engines and unless the valves seat perfectly, leaks occur between the valves and their seats, thereby causing poor compression with a corresponding loss of power. 10 A poppet valve of this kind is provided with a stem and a disc like head, which is formed with a tapered seating face as is well understood. 15 In many cases it is preferred to grind the valve stem on a centerless grinder, because of the great accuracy which is obtained in the method of grinding valve stems with a centerless grinder. The difficulty in holding a valve during the process of grinding its tapered seating face is that of preventing the valve from rotating out of its true axis and from wobbling or chattering. 20 When held in the ordinary chuck 25 of a valve grinding fixture, the valve is apt to be held off center because of the wear on the jaws of the collet and because the stem is sometimes not ground true. One of the objects of my invention is to provide a chuck 30 of novel form for holding the valve stem rigidly against any vibration and for rotating it upon its true axis whereby the tapered seating face thereof may be accurately ground into a true circle. With these ends 35 in view this invention relates to a valve grinder having a chuck provided with a collet for gripping the end of the valve stem and a valve centering collar or collet in which the valve stem is accurately centered 40 and held by a tight fit, whereby when the valve is rotated by the chuck it is caused to rotate on its true center and its tapered seating face may therefore be ground accurately and true. The invention further consists in the several novel features herein- 45 after fully set forth and claimed.

The invention is clearly illustrated in the accompanying drawing, in which:

Fig. 1 is a plan of a valve grinder embodying a simple form of the present invention, and showing a valve held in grinding position therein, certain parts of the grinding member being broken away; Fig. 2 is a vertical, longitudinal section taken on the line 2-2 of Fig. 1 upon a slightly enlarged scale; Fig. 3 is a detail sectional view, in full size,

of the end of the chuck, which contains the stem gripping collar and Fig. 4 is an end view looking in the direction of the arrow 4 in Fig. 3 with the valve removed. 60

Referring to said drawing, the reference character 5 designates the grinding member of the machine, which member embodies a grinding wheel 6 mounted on a shaft 7, which is journaled in bearings, one of which is seen at 8, and having a belt pulley 9 mounted thereon, belted to a suitable drive pulley, by means of which the grinding wheel may be rotated. These parts comprise the grinding tool of the grinding member, 65 and as usual it is capable of being moved in lines parallel with the axis of the shaft and in lines at right angles thereto whereby the grinding wheel may be fed to and across the tapered seating face of the valve 70 A, which is to be ground.

Mounted adjacent to the grinding member is a chuck fixture 10, having a base portion 11 upon which is mounted a head 12. The head is bored longitudinally and the axis of 80 the bore is set at a suitable angle with respect to the grinding face of the grinding wheel 6, an angle of 45 degrees being here shown, inasmuch as that angle is one of the standard angles of tapered seating faces of 85 poppet valves for internal combustion engines.

Secured in the bore of the head 12 is a bearing bushing 13, in which is rotatively mounted the hollow spindle 14 of the chuck. 90 A belt pulley 15 is mounted on the hollow spindle 14 and is belted to a suitable drive pulley and furnishes the means for rotating the hollow spindle 14. A flange 16 on the hollow spindle 14 bears against one end of 95 the bushing 13, and a collar 17 mounted upon said hollow spindle bears against the other end of said bushing. Nuts 18 threaded upon the outer end of the hollow spindle 14 and bearing against the collar 17, are 100 provided for securing the hollow spindle against endwise movement in the bushing. In the hollow of the hollow spindle 14 is fixedly secured a sleeve 19, which has an inferiorly tapered front end that engages with 105 the tapered outer side of the jaws 20 of a stem gripping collet 21. Said collet is adapted to grip the stem a, of the valve A, which is to be ground. The collet 21 is threaded to a tubular member 22, 110 which extends through the hollow spindle 14 and is arranged to be moved in one end-

wise direction by fingers 23 mounted upon a support 24, which is threadedly secured upon the outer end of the tubular member 22. A finger actuating collar 26 is slidably mounted on the hollow spindle 14 and has a tapered end, which engages with the fingers 23 and said collar is arranged to spread the ends of said fingers apart when forced towards said fingers to thereby cause said fingers to move the tubular member 22 in an endwise outward direction to thereby clamp the jaws of the collet 21 upon the valve stem a^1 . A hand lever 27 fulcrumed upon an arm 28 of the base 11 and provided with a fork, 29 having pins arranged to engage in a circumferential groove in the collar 26 provides means for shifting the collar 26 and thus operating the collet 21.

The collet 21 is located at a considerable distance away from the outer end of the hollow spindle 14 instead of being located at its outer end and is arranged to grip the valve stem at a place distantly removed from the valve head a^1 , and means are provided at the extreme outer end of the hollow spindle 14 for centering and gripping the valve stem at a place adjacent the valve head a^1 and said means will now be described.

30 Fixedly secured in the outer end of the hollow spindle 14 is a bushing 30, which contains a central bore 31 through which the valve stem may be inserted into the collet 21. Said bushing is provided with an externally threaded flange 32 on which is screwed a nut 33 that may be screwed against the outer face of one of the clamp nuts 18 to withdraw the bushing 30 from the hollow spindle 14. The outer end of the bushing 30 is bored out to form a cavity 34 in which is secured a valve centering collar or collet 35, which is formed with jaws 36 and the jaw portion of the collar 35 is accurately bored to fit the stem a^1 of the poppet valve. A nut 37 is threadedly secured upon the externally threaded end 38 of the bushing 30 and said nut is formed with a tapered inner face 39 which fits the tapered outer faces of the jaws 36 of the collar 35. Set screws 40 threadedly secured in the nut 37 are arranged to bear against the outer faces of the collar jaws 36 and provide means whereupon any or all of said jaws may be adjusted toward or away from the axis of rotation 41 of the chuck. When poppet valves are ground on a centerless stem grinder a very slight taper or flaring part 41 is ground upon the end of the valve stem adjacent the head of the valve, which tapered or flaring portion is concentric with the axis of the valve. When the valve stem is inserted into the chuck it becomes tightly wedged into the end of the centering collar or collet 35, because of the tapered or flaring ground portion of the valve stem, whereby when the

stem is gripped by the collet 21 and the chuck is rotated the valve will therefore be rotated upon the true axis of the valve stem and any wobbling or chattering thereof is eliminated. If desired the collar or collet 35 may be omitted and the bore 31 may extend to the front end of the bushing 30. In this case the flaring ground end of the valve stem wedges directly in the bore of the bushing.

75 Inasmuch as the valve stem sometimes becomes tightly wedged in the collar or the collet, means have been provided for freeing the valve stem from the collets. A simple form of means has been shown in the drawing and comprises a stem 42 contained in the tubular member 22 and having a reduced end portion 43 of the same diameter or a diameter slightly less than that of the valve stem and arranged to be struck against the same. 80 The other end of the stem 42 projects beyond the rear end of the hollow spindle 14 and is secured to a yoke member 44, as for instance by nuts 45 threaded on the threaded end of the stem 42 and gripping the yoke member 44 between them. Said yoke 44 is connected with the forks of the hand lever 27 by nuts 47. An adjustable collar 46 is threadedly secured upon the outer end of the stem 42 and is adapted to be forcibly brought into contact with the rear end of the tubular member 22 to thereby jar the collet 21 free in case it may become wedged tightly on the valve stem.

95 In the operation of this device, the stem of 100 the valve to be ground is inserted through the collar 35 and into the collet 21 and the hand lever 27 thereupon moved in the direction to clamp the collet 21 upon the valve stem. In inserting the valve stem into the 105 chuck the attendant forcibly presses the tapered or flaring end 41 of the valve stem into a wedging contact with the collar or collet 35 so as to make a tight fit between the two. It will be understood that both the 110 grinding wheel and the chuck are in constant rotation. The attendant then moves the grinding wheel up to the rough beveled seating face of the valve head and accomplishes the grinding operation in the usual manner, 115 grinding away sufficient material to produce a smooth surface. When finished, the attendant moves the hand lever 27 back thereby releasing the collet 21 from the valve stem and in doing so the yoke 44 is drawn forward sufficiently to bring the forward end of the reduced portion 43 of the valve ejecting stem 42 into engagement with the end of the valve stem and thereby releasing it from its wedged condition with the collet or col- 120 lar 35.

125 More or less variation of the exact details of construction is possible without departing from the spirit of this invention; I desire, therefore, not to limit myself to the ex- 130

act form of the construction shown and described, but intend, in the following claims, to point out all of the invention disclosed herein.

5 I claim as new, and desire to secure by Letters Patent:

1. In a valve grinder for grinding the tapered seating face of poppet valves, a rotary valve stem holding chuck, having an endwise movable collet therein, arranged to grip one end of the valve stem, collet actuating means, and a stem centering collar stationarily secured in the outer end of the chuck, said collar having a cylindrical bore adapted to receive the flaring head end of a valve stem and the collet being movable in a direction to wedge the flaring head end of the valve in the cylindrical bore of the collar, whereby the two ends of the valve stem are tightly held in centered position in the collar and collet.

2. In a valve grinder for grinding the tapered seating face of poppet valves, a rotary, valve stem holding chuck, having chuck clos-

ing means, a stem gripping collet in said chuck, a collar stationarily secured at the end of the chuck, said collar being formed with radially adjustable endwise engageable centering jaws, and means for radially adjusting the jaws of the collar independently of the chuck closing means.

3. In a valve grinder for grinding the tapered seating face of poppet valves, the combination of a rotary, valve stem holding chuck, having a stem gripping collet therein, 35 collet actuating means, a stem centering member at the end of the chuck and having a cylindrical bore into which the flaring head end of the valve stem is moved into a tight fit by said collet and its actuating means, a 40 valve ejecting spindle, a single hand lever and operative connections between said hand lever and the collet actuating means and between said hand lever and the valve ejecting spindle whereby the collet actuating means 45 and valve ejecting spindle are actuated simultaneously.

GEORGE R. RICH.
